(57) **CLAIM**

We claim the ornamental design for a door latch for semiconductor manufacturing equipment, as shown and described.

DESCRIPTION

FIG. 1 is a front, top and right side perspective view of a door latch for semiconductor manufacturing equipment showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a cross-sectional view take along line 8-8 in FIG. 2 thereof; and,

FIG. 9 is a perspective illustration indicating the state that a lock was opened.

The broken lines are included for the purpose of illustrating portions of the article that form no part of the claimed design.
